UNITED STATES PATENT OFFICE.

FRANK J. PIOCH, OF SAN FRANCISCO, CALIFORNIA.

GAS BURNER.

1,409,465.

Specification of Letters Patent. Patented Mar. 14, 1922.

Application filed March 25, 1920. Serial No. 368,485.

To all whom it may concern:

Be it known that I, FRANK J. PIOCH, a citizen of the United States, residing at the city and county of San Francisco and State 5 of California, have invented a new and useful Improvement in Gas Burners, of which the following is a specification.

This invention relates to a gas burner and especially to a burner of the Bunsen type.

10 One of the objects of the present invention is to provide a simple substantial gas burner of the Bunsen type and especially a burner which is adapted for enclosed heaters, bake ovens, furnaces and the like.

15 Another object of the invention is to provide a structure whereby complete combustion of the gases discharging from the burner is insured; further to provide means for regulating air admitted to support combustion and also to direct the air in such a manner that it will pass through the combustion zone before entering the furnace chamber proper.

Further objects will hereinafter appear.

20 The invention consists of the parts and the construction, combination and arrangement of parts as hereinafter more fully described and claimed, having reference to the accompanying drawings, in which—

25 Fig. 1 is a cross-section of the burner taken on line 1—1, Fig. 3.

Fig. 2 is a plan view of the burner.

Fig. 3 is a central vertical longitudinal section taken on line 3—3, Fig. 1.

30 Referring to the drawings in detail, A indicates a furnace of any suitable construction interior of which is formed a combustion chamber 2. Connected with said chamber is a discharge flue 3, and formed in the bottom of the furnace is an air admitting opening 4. Forming a cover for said opening is a plate 5, and formed in said plate is a plurality of perforations or openings 6. Mounted below the plate 5 and spaced with

40 relation thereto is a gas burner generally indicated at B. This burner consists of a nozzle 7, a mixing casing 8, an elbow 9, and a mixing tube 10. Turnably mounted on the nozzle 7 is a damper plate 11, and adapted to regulate the flow of gas through the nozzle is a valve 12 of suitable construction. Formed in the mixing tube 10 is a plurality of discharge openings 14, and forming a closure for one end of the tube is a stopper 50 15, here illustrated as a plug.

There are two rows of discharge openings

14 formed in the tube 10 in the present instance, and by referring to Figs. 1, 2 and 3, it will be seen that said openings align with the perforations 6 formed in the plate 5. 60 This is of great importance as a jet action is formed between the openings 14 and 6 when the gas discharges therethrough and an induced flow of air is in this manner obtained, which materially improves combustion with- 65 in the chamber 2.

The burner here shown is particularly adapted for enclosed heaters, bake ovens, furnaces and the like. The heater or furnace here shown is provided with a single 70 air intake opening 4 and this is covered by the plate 5 as previously stated. All air admitted to the furnace must therefore pass through the openings 6 in the plate, and as said air flow is induced by the jet action of 75 the gas discharging through the openings 14, it can readily be seen that an intimate mixture of gas and air is obtained which, practically speaking, insures complete combustion of all the gases discharged by the burner. 80

In actual practice it will be seen that when the valve 12 is opened, gas will discharge through the nozzle 7 in an upward direction through the mixing casing 8 and the elbow 9. A jet action is here formed which induces 85 the flow through the damper openings 11, the volume of air admitted at this point being regulated by adjusting the position of the damper in the usual manner. The mixture of air and gas obtained by this action 90 passes through the tube 10 and finally discharges through the burner openings 14 formed therein. A second jet action is formed when the gas discharges upwardly through the perforations in the plates 5 and 95 6 an induced flow or a secondary mixing action of gas and air is thus obtained which materially increases the efficiency of the burner.

In actual practice it is found that the heat is intense and to all practical purposes might 100 be compared with a welding flame. With the perforated plate 5 removed, I find that a long flame of intense blue color is formed by the gas discharging from each burner opening 14, and that with the plate 5 in position a shorter flame is produced which is rather white in color. This flame produces more heat than the blue flame otherwise formed and I think this is due to the perfect mixture of air and gas obtained by the 105 induction action produced by the gas discharging through perforations in the plate,

and as said perforations are the only openings through which air can be admitted, it can readily be seen that all air must pass through the combustion area before it can 5 enter the furnace chamber proper.

While circular openings are here shown as formed both in the burner and the perforated plate 5, I wish it understood that slot-like or other shaped openings may be employed. The important feature to be observed however in constructing a burner of this character is first of all a correct spacing between the plate and the burner proper, and secondly, provision of openings in the 15 perforated plate which are considerably larger in area than the discharge openings in the burner. Other variations in design and construction may obviously be resorted to within the scope of the appended claim. 20 I also wish it understood that the materials and finish of the several parts employed may be such as the experience and judgment of the manufacturer may dictate or varying conditions may demand.

25 Having thus described my invention, what I claim and desire to secure by Letters Patent is—

The combination with the casing having a combustion chamber formed therein, of a 30 rectangular shaped opening formed in the

bottom of the casing, a discharge opening formed in the casing for the escape of products of combustion, said discharge opening and said rectangular opening being the only openings communicating with the combustion chamber, a rectangular shaped plate forming a closure for the bottom opening, two rows of perforations formed in said plate, a pipe disposed below said plate and spaced therefrom, said pipe being parallel 35 with the longitudinal axis of the plate, two rows of perforations formed in the pipe and aligning with the perforations in the plate, lugs formed on the pipe engaging the bottom of the plate and determining the spacing between the pipe and the plate, means for securing the lugs with relation to the plate to support the pipe, and means for delivering a combustible mixture of air and gas to the pipe, said mixture discharging 40 through the perforations in the pipe and upwardly into the combustion chamber through the perforations in the plate.

In testimony whereof I have hereunto set my hand in the presence of two subscribing 45 witnesses.

FRANK J. PIOCH.
